US00D783474S

(12) **United States Design Patent** (10) **Patent No.:** **US D783,474 S**
(45) **Date of Patent:** **** Apr. 11, 2017**

(54) **BRAKE**

(71) Applicant: **Ausco Products, Inc.**, Benton Harbor, MI (US)

(72) Inventors: **Brian P. Dennis**, Kalamazoo, MI (US); **Nancy L. Leonard**, Dowagiac, MI (US); **Howard H. Baldeosingh**, Stevensville, MI (US)

(73) Assignee: **Ausco Products, Inc.**, Benton Harbor, MI (US)

(**) Term: **15 Years**

(21) Appl. No.: **29/562,721**

(22) Filed: **Apr. 28, 2016**

(51) LOC (10) Cl. **12-16**

(52) U.S. Cl.

USPC **D12/179; D12/180**

(57) **CLAIM**

The ornamental design for a brake, as shown and described.

DESCRIPTION

FIG. 1 is a top, front, left side perspective view of a brake showing our new design;

FIG. 2 is a top, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

(Continued)

The broken lines in all Fig. views illustrate portions of the brake that form no part of the claimed design.

1 Claim, 8 Drawing Sheets
